UNITED STATES PATENT OFFICE.

EMILE ERICSON, OF PELHAM, AND ROGER WEISS, OF BROOKLYN, NEW YORK, ASSIGNEES
TO HOBBS WALL PAPER COMPANY, A CORPORATION OF NEW JERSEY.

DESIGN FOR A BORDER FOR WALL-PAPER.

50,243.

Specification for Design.

Patented Jan. 30, 1917.

Application filed November 13, 1916. Serial No. 131,150. Term of patent $3\frac{1}{2}$ years.

To all whom it may concern:

Be it known that we, EMILE ERICSON and ROGER WEISS, both citizens of the United States, residing, respectively, in Pelham, county of Westchester, State of New York, and Brooklyn, county of Kings, State of New York, have jointly invented a new, original, and ornamental Design for a Border for Wall-Paper; and we hereby declare the following to be a description of the same in such terms as will enable persons skilled in the art to which it appertains to make and use the same, reference being had to the accompanying drawings.

The figure of the drawing is a plan view of a portion of a wall paper border illustrating our new design.

Copies of this patent may be obtained for five cents each, by addressing the "Commissioner of Patents, Washington, D. C."

The design comprises a central panel, A, containing figures and a bunch of flowers, B. On each side of the panel is a branch carrying leaves and flowers C.

The design as shown is intended to be repeated or matched out upon either side indefinitely as is usual in such cases.

What we claim is:—

The ornamental design for a border for wall paper as shown and described.

EMILE ERICSON.
ROGER WEISS.
